DESIGN FOR A COSMETIC BOTTLE

Pauline W. Shulman, Hartford, Conn., assignor to Martha T. Marcus

Application April 22, 1936, Serial No. 62,236

Term of patent 14 years

To all whom it may concern:

Be it known that I, Pauline W. Shulman, a citizen of the United States, residing at Hartford, in the county of Hartford and State of Connecticut, have invented a certain new, original, and ornamental Design for a Cosmetic Bottle, of which the following is a specification, reference being had to the accompanying drawing, forming part thereof.

In the drawing,—

I claim:—

The ornamental design for a cosmetic bottle, substantially as shown.

PAULINE W. SHULMAN,
